UNITED STATES PATENT OFFICE.

SEYMOUR W. BONSALL, OF NEW YORK, N. Y.

COAT-HANGER.

No. 920,894.

Specification of Letters Patent.

Patented May 4, 1909.

Original application filed April 29, 1908, Serial No. 430,019. Divided and this application filed May 28, 1908.
Serial No. 435,384.

To all whom it may concern:

Be it known that I, SEYMOUR W. BONSALL, a citizen of the United States, residing in the borough of Manhattan, city, county, and 5 State of New York, have invented a certain new and useful Improvement in Coat-Hangers, of which the following is a specification.

My invention comprises an improved portable coat-folding hanger, whereby men's coats may be properly suspended as folded with shoulders touching. By the use of 10 this form of hanger, the coats may be accommodated, while suspended in a row and in 15 contact, within a narrower space than would otherwise be possible.

The invention is illustrated in a preferred form in the accompanying drawings wherein—

20 Figure 1 is a perspective view of a modified form of my device, showing the mode of use of my coat-folding hanger, Fig. 2 is a side view of a portion of the coat-folding hanger in folding position, Fig. 3 is a sectional view on the plane *a—b* of Fig. 2, Fig. 4 is an elevation of the hanger joint showing 25 a preferred mode of hanging the same on the suspension bar shown in section, and Fig. 5 is a top view of the preferred alining 30 device together with the hanger hook, showing their relative positions when a coat is suspended.

I have shown my improved hanger in Fig. 1 as used with one form of improved 35 salesman's trunk shown in my pending application for improvement in trunks, filed April 29th, 1908, Serial No. 430,019, of which this application is a division. It is to be understood, however, that the improved 40 hanger hereinafter claimed may be used in any suitable location without departing from my present invention.

In Fig. 1 of the accompanying drawings, a trunk body 1 is provided with a suspension 45 bar 2 having legs 3 passing through suitable guides 4 in the interior of the trunk, which legs are attached to springs, 5, which exert a tendency to lift the bar 2 and the legs 3.

My improved coat-folding hanger is adapted 50 to support a man's coat either in the usual open position shown in dotted lines on the left in Fig. 1, or in the folded position as shown on the right in said figure. The peculiar usefulness of this form of hanger when 55 employed in combination with the special

trunk construction above described is fully set forth in my aforesaid earlier application for patent and need not be elaborated here.

In its preferred form, the hanger consists of two arms 6, pivoted to a common head 7, 50 at such a distance apart that, when the arms are turned parallel each to the other, as shown in Fig. 5, there will be enough space between them to accommodate the folds of a coat when in the folded position indicated 55 on the right in Fig. 1. A suspension hook, 8, is attached to the head 7.

I prefer to provide the head 7 with a middle rib, 9, so placed that, when the arms 6 are brought into parallel position, they bear 70 against the sides of said rib. I also prefer to shape the ends of the arms 6, as shown, so that, when extended (as in Fig. 4) these ends shall abut against the opposite sides of the rib 9, thus holding them in line and preventing their swinging toward each other on the wrong side of the head. 75

In Fig. 4 is shown the preferred form of the spaces at each side of the head 7, wherein the arms 6 are pivoted and in which they 80 swing. It will be seen that the top and bottom of each of these spaces is inclined upward toward the back and that the pivots on which the arms 6 swing, shown in dotted lines at 10 are correspondingly inclined. 85 Owing to this preferred construction, the arms when in parallel position, (as in Figs. 2 and 3) will support the folded coat without any tendency to swing apart, while, on the other hand, as soon as these arms are separated, the weight of the coat will tend to bring them into the open position shown on the left in Fig. 3, and thereafter this gravitational action will act to keep the arms in line and prevent all tendency toward accidental folding movement. 90

In using the coat-folding hangers with external supporting means I prefer to make the hooks 8 revoluble in the heads 7 to facilitate the operation hereinafter described. 100 The external supporting means preferred will be a suspension bar substantially equivalent to that shown at 2 in Fig. 1, although this is not indispensable to the use of my improved hangers. When so used, the top 10 of each hook 8 should fit snugly over the suspension bar, and the hangers should normally take the position of the right hand hanger in Fig. 1, so that the folded coats lie snugly against each other in a row, suspend- 11.

ed from the bar 2, and preferably so that the individual hangers can be slid along said bar, although this is not essential. It is obvious that, by hanging the coats thus folded they can be accommodated within a narrower space than when hung open as formerly. To facilitate securing the coat in place, the suspending hook may be slipped through the usual tape provided at the collar, or other means for this purpose may be provided. When coats are thus hung, it is obvious that any one of them may be separately unfolded without removing the hanger from its support, and may be exhibited without disturbing any coat not wanted. Owing to the construction of the head 7 and the preferred arrangement of pivots 10, the coats will be held open automatically.

In order to secure greater regularity and certainty of action in carrying out the operation above described, I prefer to combine the elements above set out with alining means whereby each hook 8 may be kept substantially at right angles to the suspension bar 5. 25 A separate means may be provided for each hook. I also prefer to make the alining devices capable of sliding along a suspension bar. In the preferred form shown, each alining device consists of a wire clip 11, bent 30 over and sliding easily upon the suspension bar 2, so as to be easily removable therefrom. At the two ends of each clip, loops or openings 12 are provided, and these are placed in a line crossing the bar 2. When the 35 hook 8 is hung, upon the bar 2, its tip passes through the openings or loops 12 (see Figs. 4 and 5) and the hook is thus kept in proper line with respect to the suspension bar 5. By this means is corrected all tendency of 40 the hanger with its hook to swing or tilt, to hang crookedly or otherwise give trouble when it is desired to fold or unfold any given garment, and the operations above described may be carried out with ease, rapidity and 45 certainty. At the same time there is no interference with the process of putting on and taking off the hangers.

It is obvious that the hangers and alining devices may be made and sold together as 50 separate articles of manufacture and may be attached to suspension bars or their equivalents already in place.

Various changes may be made in my invention without departing from the scope 55 of my claims and I do not limit myself to the details herein shown and described.

What I claim is—

1. A coat-folding hanger comprising a relatively narrow head, a pair of arms considerably longer than the width of said head, pivoted to opposite sides of said head in such a position as to be adapted to come together in the same plane behind the head, with sufficient space between them to accommodate

the folds at the neck of a folded coat, and 65 suspending means for said head and arms, substantially as described.

2. A coat-folding hanger comprising a head, a pair of arms pivoted thereto and so placed as to accommodate the folds at the 70 neck of a folded coat between them when they are turned as near together as possible, and suspending means for said head and arms, substantially as described.

3. A coat-folding hanger comprising a 75 head having two spaces separated by a transverse partition, arms pivoted within said spaces and adapted to abut against said partition so as to be held in line by it, and means for suspending said head and arms, substantially as described.

4. A coat-folding hanger comprising a head and a pair of arms turning on pivots fixed in said head, said pivots being inclined to the horizontal when said head is in normal 85 position, substantially as described.

5. A coat-folding hanger comprising a head having side spaces cut therein at an angle to the horizontal plane, a pair of arms pivoted within said spaces and a suspending 90 means attached to said head, substantially as described.

6. A coat folding hanger comprising a head having side spaces cut therein at an angle to the horizontal plane, a pair of arms 95 pivoted within said spaces and spaced apart to accommodate the folds of a folded coat between them, and a suspending means attached to said head, substantially as described.

7. As an article of manufacture, a coat-folding hanger adapted for attachment to a suspension bar comprising an alining device adapted to engage such bar and a foldable coat supporting means adapted to engage 105 said alining device and said suspension bar, substantially as described.

8. As an article of manufacture, a coat-folding hanger adapted for attachment to a suspension bar comprising a bent metal clip 110 adapted to embrace the bar and having openings at its ends and a foldable coat supporting means having a hook adapted to hang over said bar and pass through said openings in said alining device, substantially as described.

9. A coat-folding hanger comprising a head, a pair of arms pivoted thereto and so placed as to accommodate the folds of a folded coat between them when brought substantially parallel, means on said head for limiting the swing of each arm in one direction, and means for suspending said head and arms, substantially as described.
